UNITED STATES PATENT OFFICE.

EDGAR EBERLY AND WILLIAM G. FETROW, OF MECHANICSBURG, PENNSYLVANIA.

SHEAF-HOIST.

1,371,777.

Specification of Letters Patent. Patented Mar. 15, 1921.

Application filed November 20, 1919. Serial No. 339,484.

To all whom it may concern:

Be it known that we, EDGAR EBERLY and WILLIAM G. FETROW, citizens of the United States, and residents of Mechanicsburg, in 5 the county of Cumberland and State of Pennsylvania, have invented a new and Improved Sheaf-Hoist, of which the following is a description.

Our invention relates to sheaf hoists and 10 particularly to sheaf hoists of the general type shown in United States Letters Patents No. 1,114,454, and No. 1,203,514, granted to us October 20, 1914 and October 31, 1916, respectively.

15 The general object of our present invention is to provide a sheaf hoist of the indicated type improved in various particulars, especially with respect to the provision of sheaf-throwing means arranged at the upper 20 end of the hoist for taking the sheaves from the elevating conveyer and throwing them to a mow as well as with respect to other important features including a novel means of mounting the hoist to be laterally swing- 25 able when desired through an arc to variously direct the sheaves to the mow.

The above and other distinctive features are hereafter particularly described and defined in the claims.

30 Reference is to be had to the accompanying drawings forming a part of this specification, it being understood that the drawings are merely illustrative of one example of the invention.

35 Figure 1 is a side elevation of a sheaf hoist constructed in accordance with our invention;

Fig. 2 is a front view thereof;

Fig. 3 is a plan view;

40 Fig. 4 is a sectional side elevation on an enlarged scale of the lower portion of the hoist;

Fig. 5 is an enlarged sectional plan view on the line 5—5, Fig. 1.

45 In carrying out our invention in practice, in accordance with the particular example illustrated, a bracket 10 is provided forming the supporting means at the lower end of the hoist, said bracket being swing- 50 ably mounted, for which purpose in the construction illustrated a vertical sleeve 11 integral therewith is disposed between upper and lower brackets 13 to which said sleeve is secured by a bolt 12 passing therethrough, 55 the brackets being bolted or otherwise secured to a post 14 or other fixed support,

the post being here shown as adjacent to a barn A represented in part. The front end of the bracket 10 is formed with a fork 15 on which a frame 16 is supported to be 60 readily detached when desired. The bracket 10 is ordinarily maintained against swinging movement by a brace 17, here shown as having a laterally bent hooked rear end 18 engaging a pin 19 on the barn A, the 65 front end of said brace being secured by a bolt 20 to a lug 21 on the fork 15. The arrangement permits the brace 17 to unhook itself from the pin 19 should a wagon part, for example, strike the lower portion 70 of the structure, in which case the unhooking of the brace will permit the structure to yield at the bottom and have a limited movement about the axis of the bolt 12, the mast springing sufficiently to permit this 75 yielding of the structure in response to a blow, thereby preventing damage to the structure.

The frame 16 extends vertically and has an open side giving the frame in general 80 a U-shape and at the lower end said frame presents a vertical bearing 22 having the lower end 23 thereof reduced to be received between the members of fork 15 and to present a shoulder at the base of said reduced 85 portion so that the bearing 22 rests on top of said fork and may be readily disengaged therefrom by a lateral movement when desired. A short vertical shaft 24 extends upwardly through the bearing members 22, 90 23 and is provided with a belt pulley 25 or equivalent driving element. The shaft 24 serves to drive the elevating conveyer of the hoist through gearing which in the present example is as follows: A bevel pinion 26 on the upper end of shaft 24 meshes with a bevel gear wheel 27 on a transverse shaft 28 having a bearing in the frame 16, and a pinion 29 turning with the shaft 28 95 meshes with a pinion 30 on a counter-shaft 100 31 turning in the frame 16 and having keyed thereto a sprocket pulley 32 over which an endless hoist chain 33 runs, said chain having fingers 34 to engage the sheaves. A housing 16^a on frame 16 serves 105 to house the gear elements on said frame.

A mast 35 is stepped in the upper end of the frame 16 which is provided for the purpose with a socket 16^b having a set screw 16^b to hold the mast against turning in the 110 socket. The chain 33, at the upper end of the hoist, runs over a sprocket pulley 36 on

a transverse shaft 37 supported in a frame 38 suitably fastened as at 39 to the mast 35 at the top. Said frame 38 in the preferred form of the invention presents an arm 40 extending forwardly in front of the mast and carrying a toothed wheel or roller 41 from which the front run of the belt passes to pulley 36. The frame 38 presents rearwardly extending side arms 42 in the rear ends of which the transverse shaft 43 is journaled, said shaft having a sprocket pulley 44 over which a chain 45 runs, the front end of said chain running over a second sprocket pulley 36^a turning with the shaft 37 or upper shaft of the elevator which shaft serves to drive said chain 45 and the pulley 44. Secured to said shaft 43 to turn therewith and thus distant from the upper sprocket shaft 37 of the elevator is a sheaf 20 throwing means to take the sheaves from the elevating fingers 34 and throw the same to a mow, the illustrated means for the purpose consisting of paddle-like blades 46 carried by side bars 47 having brackets 48 thereon keyed to the shaft 43, two of said throwing elements 46 being employed, disposed at the sides of the chain 33, the arrangement being such that the revolving elements 46 come beneath the sheaf at a finger 34 as the latter approaches the upper sprocket 36 so that the sheaf is carried rearwardly in the arc of a circle and thrown to the top of the mow. The shaft 43 has its bearing portions 37^a preferably coned as indicated in Fig. 3, the brackets 48 presenting corresponding bearings. The frame 38 is braced by obliquely disposed bars 49 secured at their upper ends to the side bars 42 by bolts 49^a and secured at their lower ends to a collar 50 adjustable vertically on the mast 35 and adapted to be secured by a set screw 51. By the described arrangement the frame 38 can be adjusted vertically about the bolt or pin 39 to properly position said 45 frame.

The sheaves to be taken up by the chain 33 are placed in succession in a cradle 52 in the form of approximately U-shaped fingers secured to the outer ends of a cross bar 53 having a hub or collar 54 fast on the mast 35.

A tightener 55 is provided for the chain 45 and consists of a plate overlying the upper run of said chain. The plate 55 is rigid with a depending bracket 56 having a vertical slot 57 through which one of the bolts 49^a passes, whereby the tightener may be vertically adjusted relatively to the chain to exert more or less pressure thereon.

60 With the described arrangement power applied to the drive gear as by a belt (not shown) running over the pulley 25 actuates through the described gearing the hoist chain 33 and the sheaf-thrower elements 46 being revolved by the driven shaft 43 will

lift the sheaves from the chain as they arrive at the top of the hoist.

For tightening the chain 33 the upper portion 35^a of the mast 35 telescopes in the lower part, the latter having a rigid collar 70 35^b thereon provided with a set screw 35^c. To raise or lower the upper portion of the mast 35 means is provided as follows: A band 58 embraces the telescoping section 35^a and constitutes a holding dog and an upper band 59 embracing said section constitutes a lifting dog. A hand lever 60 is fulcrumed near one end on the upper end of a supporting bar 61 which is secured at its lower end as at 62 to the collar 35^b or other fixed part of the mast structure and the front arm of said lever is connected as by a link 63 with the lifting dog 59. The holding dog 58 has an arm 64 extending therefrom and affording support for the same by reason of the arm extending between the two sides of the bar 61, a portion of said bar being broken away in Fig. 1. Thus, the lever 60 may be rocked upwardly to release the band 59 from the mast section 35^a and drop said band so that with the downward rocking of the lever 60 and the raising of the band 59, the latter will grip the mast section and raise the same. The dog 58 releases itself automatically to permit the lifting of the mast section 35^a but grips said section to prevent the same from dropping. Any suitable bracing means may be provided for the upper portion of the mast, there being shown a brace 65 the sides of which flare from mast 37 as seen in Fig. 2. Said brace 65 is secured to any fixed part of a barn structure, for example, there being indicated a beam 66. On the front end of the brace 65 is a U-bolt 67 embracing the mast section 35^a. In the raising of the mast section 35^a for tightening the chain 33, the U-bolt 67 will be first loosened. Also, the U-bolt 67 may be loosened to permit the hoist structure to be turned in the bearing 110 fork 15 to vary within the limits permitted by the flare of brace 65, the direction in which the sheaves are thrown, the tightening of the bolt serving to hold the structure in position with the sheaf-throwing elements 115 46 disposed in a given direction.

We would state in conclusion that while the illustrated example constitutes a practical embodiment of our invention, we do not limit ourselves strictly to the mechanical details 120 herein illustrated, since manifestly the same can be considerably varied without departure from the spirit of the invention as defined in the appended claims.

Having thus described our invention, we 125 claim:

1. A sheaf hoist including a supported mast, an endless sheaf-carrying chain, a sprocket pulley adjacent to the lower end of the mast over which said chain runs, a frame 130

on said mast at the upper end, a sprocket pulley mounted in said frame over which said chain runs at the upper end, a shaft mounted in said frame laterally distant from 5 said upper end of said chain, means to turn said shaft with the turning of the second-mentioned sprocket pulley, and sheaf-throwing elements secured at one end on said shaft to turn therewith, said elements being disposed at each side of the chain and of a 10 length to turn at their outer ends in paths adjacent to the chain to lift the sheaves from the latter and throw the same away from the hoist.

15 2. A sheaf hoist including a supported mast, an endless sheaf-carrying chain, a sprocket pulley adjacent to the lower end of the mast, a frame on the mast at the upper end, a sprocket pulley mounted in said frame 20 and over which said chain runs at the upper end, means pivotally mounting said frame on the mast, a brace secured at its upper end to said frame and adjustably secured at its lower end to the mast to permit adjustment 25 of said frame in a vertical plane, sheaf-throwing means revolvably mounted in said frame remote from the upper end of said chain and said second pulley, means to drive said sheaf-throwing means with the turning 30 of the second pulley, and a belt-engaging arm on said frame at the front.

3. A sheaf hoist including a mast, sheaf-elevating means carried by the mast, a frame at the lower end of said mast and carrying 35 the same, drive means mounted in said frame to actuate said elevating means, a bracket on which said frame is supported, said bracket

being swingably mounted, and detachable brace means for said bracket.

4. A sheaf hoist including a mast, a frame 40 in which said mast is stepped, sheaf-elevating means adapted to carry sheaves upwardly to the top of the mast, drive means for said chain, swingable means mounting said frame, a brace adapted to prevent said 45 last-mentioned means from swinging, a fixed support, and means on said support engaged by said brace, said brace being self-detaching from said last-mentioned means when the bracket is swung in one direction. 50

5. A sheaf hoist including a frame, a mast thereon, hoisting means associated with the frame and mast, and a bracket presenting a fork, said frame having a member supported on said fork and removable therefrom by a lateral movement, together with releasable means to hold the mast against accidental disengagement from the fork. 55

6. A sheaf hoist including a frame, a mast thereon, hoisting means associated with the 60 frame and mast, a bracket presenting a horizontal fork, a vertical bearing member on said frame and extending through the fork, said bearing member having support on the fork at the top, a vertical shaft extending 65 through said bearing, means whereby said shaft may be driven, and a drive connection between said shaft and the hoisting means, together with releasable means to hold the mast against accidental disengagement from 70 the fork.

EDGAR EBERLY.
WILLIAM G. FETROW.
